CLAIM

I claim the ornamental design for a battery pack, as shown and described.

DESCRIPTION

FIG. 1 is a perspective view of a battery pack showing my new design;

FIG. 2 is a right side view of the battery pack of FIG. 1;

FIG. 3 is a left side view of the battery pack of FIG. 1;

FIG. 4 is a rear view of the battery pack of FIG. 1;

FIG. 5 is a front view of the battery pack of FIG. 1;

FIG. 6 is a top view of the battery pack of FIG. 1; and,

FIG. 7 is a bottom view of the battery pack of FIG. 1.

The evenly spaced broken lines illustrate portions of the article that form no part of the claimed design. The dot-dash broken lines illustrate a boundary to the claimed design and form no part thereof.
